R. F. JACOB.
SAFETY LOCK FOR SWITCH STANDS.
APPLICATION FILED SEPT. 30, 1908.

Patented May 11, 1909.

UNITED STATES PATENT OFFICE.

RICHARD FELDER JACOB, OF MOBILE, ALABAMA, ASSIGNOR, BY DIRECT AND MESNE ASSIGNMENTS, OF ONE-HALF TO BURKE B. HOLLOWAY, OF SELMA, ALABAMA, ONE-SIXTH TO C. A. WICKERSHAM, OF ATLANTA, GEORGIA, AND ONE-SIXTH TO O. T. NELSON, AND ONE-SIXTH TO A. MORITZ, OF MONTGOMERY, ALABAMA.

SAFETY-LOCK FOR SWITCH-STANDS.

No. 921,544.

Specification of Letters Patent.

Patented May 11, 1909.

Application filed September 30, 1908. Serial No. 455,540.

To all whom it may concern:

Be it known that I, RICHARD FELDER JACOB, a citizen of the United States, residing at Mobile, in the county of Mobile and State of Alabama, have invented certain new and useful Improvements in Safety-Locks for Switch-Stands; and I do hereby declare the following to be a full, clear, and exact description of the invention, such as will enable others skilled in the art to which it appertains to make and use the same.

This invention consists in a safety lock for switch stands, of any kind whatsoever, and constitutes an improvement over the lock claimed in the prior patent No. 865,904, dated September 10, 1907.

The object of the invention is to provide a safety lock for switch stands which shall be simple and certain in operation, not liable to freeze in cold climates, will be easy to manufacture, one which with slight alterations may be put on or detached to those switch stands that are now in use, and which will prevent the key from falling out when the semaphore is unlocked.

To these ends the invention consists in the lock, and combination of parts hereinafter more fully described, and particularly pointed out in the claims.

Referring to the accompanying drawings forming a part of this specification, Figures 1 and 1^a represent elevational views of a switch stand provided with the improved safety lock. Fig. 2 is a view on the line 2—2 of Fig. 3, showing the device in locked position on the lever. Fig. 3 is a view of a portion of the lever looking from the inside outward, showing how the lock is attached to the lever, and also the lug on the stand in section. Fig. 4 is a perspective of the lug attached to the stand. Fig. 5 is an elevational view of the lock detached, with its cover removed and showing the bolt engaging the lug on the stand. Fig. 6 is a sectional view, taken on the line 6—6 of Fig. 5.

Like letters of reference indicate like parts in all the views.

A represents the body of the switch stand, B its base, C the semaphore rod belonging to the said stand, and D a lever or other suitable controlling device for the semaphore, which is adapted to be locked to the stand A. In carrying out the invention, there is provided a recess L on the lever, or other

suitable lock holding device, as shown in Figs. 2 and 3, which is adapted to receive a lock E, of any suitable and approved construction, and to protect the same from water, as will appear more fully below. Said lock is provided with a key G. This key, of course, may be of any kind whatsoever approved by the road, and the proper employees are provided with the usual duplicates.

On the stand A, there is the usual lug a, which may be integrally cast with the body A of the stand, or otherwise secured thereto; and it is provided with a notch a', or other suitable means, by which the bolt E' of the lock E may engage the same. The said lock is provided with any suitable device, in this instance shown as a bolt E' adapted to engage the notch a', and integrally attached to said bolt, or otherwise permanently fastened thereto, is the extension E² provided with a notch E³, and which has a lug provided with the edge e³ and flat top e⁴, as shown in Figs. 5 and 6. The edge e³ is so spaced with reference to the upper edge e⁵ of the key hole, that it lies slightly above the latter when the semaphore is locked as shown in full lines in Fig. 5, and below the latter when the semaphore is unlocked as indicated in dotted lines in said figure, for a purpose to be presently described.

F represents a spring controlling the bolt E', but, of course, said bolt may be operated by gravity, if desired. This spring is secured in the lock in any desired manner, for example, as by fitting in the top of the bolt E' and against the inside of the top wall of the lock E, as shown; or it may be a spring of any other shape, found desirable, and suitably attached in the lock. The function of this spring is, of course, to hold the bolt securely in its locked position in the notch a' of the lug a, and thereby prevent the said bolt from being shaken out of the said notch by passing trains or otherwise. Another important function of this spring is to have its tension such that when the semaphore is not locked and the bolt E' is not in contact with the lug a, the said spring will cause the lower edge of the said bolt to occupy the position shown in the dotted line a² in Fig. 5, in which position the edge e³ of the said slot E³, will occupy the position below the edge e⁵ of the key hole likewise shown in dotted lines. In this lat-

ter position, as will be observed, the said edge e^3 partially closes the key hole slot, and therefore prevents a key from entering or leaving the lock. Of course the degree of closing the said slot may be regulated at will, and the bolt E' may be given any length of travel desired, according to the key used, and in many cases it will be desirable to allow enough space between the lower edge of the extensions E^2 and the inner surface of the lower wall of the lock E , to permit the said edge e^3 to entirely close the key hole slot. In addition to the action of the edge e^3 , just described in the present invention, the top e^4 of 15 said lug is, for the purpose stated below, extended all the way from one flat face wall of the lock to the other, as best shown in Fig. 6. The lock fits snugly in the slot or recess L in the lever D , is held therein by the plate e 20 which also constitutes a water tight cover.

In the lock claimed in the prior patent above, the edges of the slot E^3 were so disposed relative to the key hole that the key could only be inserted, or withdrawn, when 25 the switch was locked in its main line position. While this is an exceedingly desirable result, yet, it has been found that on some of the switch stands now in use, for example the type shown in Figs. 1 and 1^a it is desirable to 30 have the key removable when the semaphore is in the side track as well as when it is in the main line position, and therefore the edges of said slot E^3 have in this invention been so disposed as to permit this. Furthermore, in 35 said prior patent the top of the lug on which the edge e^3 occurs was shown in Fig. 7 of said patent, as not extending from one wall to the other of said lock, but on the contrary was provided with a recess through which the 40 ward of the key might pass. It has been since found that the ward of the key is liable, when turned the wrong way, to pass through said recess, and become caught between said lug and the upper portion of said bolt E' . To 45 prevent such accidents the top e^4 of said lug is, in the present invention, made to extend solidly from one wall to the other of said lock, as above stated.

It will be observed that since the lock is 50 water tight, except for the bolt and key hole, and securely fastened in the recess L , that it is not possible for rain to enter the same except through said key hole. These holes, in practice, are either made too small to permit 55 sufficient water to enter to accomplish freezing in cold climates or else they are guarded by slots extending around the same, or lips partially overhanging them. In all cases, 60 any small quantity of water that enters by this channel is immediately drained out around the bolt E' , which extends downwardly as shown. Furthermore, the bolt E' and extension E^2 fit snugly the interior walls of the lock, and have the extensive bearings 65 on the four inside walls, as illustrated. These

bearings serve to give an easy and certain action of the bolt under the influence of the key and also to leave practically no space for the collection of water, which might later freeze and render difficult the operation of the lock. 70 The parts being thus made heavy and strong, are capable of being formed by simple castings, which features are both very important in the railroad service, where the locks receive the roughest kind of usage and where 75 they must be made in very large numbers.

In operation, the lever being locked to the lug a on the switch stand, the key is inserted, the bolt E' withdrawn from its lug, and the switch thrown. While the lever D remains 80 unlocked, the bolt E' is forced by gravity, or the spring F , or both, to its dotted line position shown in Fig. 5, and the edge e^3 crosses the edge e^5 of the key hole and prevents the key from being withdrawn. If the key is 85 turned the wrong way, the top e^4 of the lug on which the edge e^3 occurs will not permit the key to pass it, but will simply cause the key to raise the bolt.

Of course it is to be understood that this 90 lock is adapted to be placed on switch stands provided with a plurality of lugs, as well as on those provided with a simple lug.

Having now described the invention what 95 is claimed is:—

1. In a safety lock for switch stands, the combination of the main body of the stand having lock engaging means, a part attached to said body adapted to receive a lock, a lock in said part adapted to be operated by a key, having a bolt adapted to contact with said lock engaging means and to occupy raised and lowered positions; and means rigidly attached to said bolt adapted to prevent the withdrawal of said key when the bolt is 100 lowered, but adapted to permit the withdrawal of said key in all raised positions of said bolt, substantially as described.

2. In a safety lock for a switch stand, the combination with the body of a stand having a lug provided with lock engaging means permanently attached to said stand; a lever permanently attached to said stand; a key operated lock permanently attached to said lever and having a bolt adapted to be raised 110 and lowered and to engage the said means on the said lug; and means rigidly attached to said bolt whereby said key cannot enter said lock or be withdrawn therefrom when the bolt is lowered, but adapted to permit 115 the withdrawal of said key in all raised positions of said bolt, substantially as described.

3. In a safety lock for a switch stand, the combination with the body of a stand provided with a lug having a notch permanently attached to said stand; a pivoted lever provided with a key operated lock having a bolt adapted to be raised and lowered, engaging said notch; and an extension rig- 125 130

idly attached to said bolt and provided with a lug extending from one face of the lock to the other and adapted to prevent said key from entering said lock or being withdrawn 5 therefrom when the bolt is lowered, but adapted to permit the withdrawal of said key in all raised positions of said bolt, substantially as described.

4. In a safety lock for a switch stand, the combination with the body of the stand; a lug rigid therewith, and provided with a bolt engaging notch; a lever pivoted to said stand and provided with a recess; a lock E having a key hole secured in said recess on 10 the side of said lever that contacts with or lies near said stand; said lock provided with a key and a bolt E' adapted to be raised and lowered and to engage said notch; an extension rigid with said bolt and having a recess provided with an edge e³ adapted to pass over and obstruct the key hole; and a spring for pressing said bolt downward, whereby said edge e³ will prevent the insertion of a key into or its withdrawal from 15 said key hole when the bolt is lowered, but will permit the withdrawal of said key in all raised positions of said bolt, substantially as described.

5. In a safety lock for a switch stand, the combination with the body of a stand provided with a lug having a lock engaging means permanently attached to said stand; a lever permanently attached to said stand; a key operated lock having a casing permanently attached to said lever; a water tight cover for said lock; said lock also having a bolt to engage the said means on the said lug; and means provided with a lug rigidly attached to said bolt, adapted to obstruct 20 the key hole when said bolt is in its lowest position; said bolt and means extending from side to side and contacting with the

four inner walls of said casing to form extended bearings, substantially as described.

6. In a safety lock for a switch stand, the combination with the body of a stand provided with a lug having a notch; a pivoted lever provided with a substantially water tight lock adapted to be operated by a key, said lock having a bolt adapted to engage 45 said notch; a spring normally forcing said bolt downward; said bolt provided with an integral extension having a lug extending from one face of the lock to the other provided with an edge e³ adapted to move across 50 the key hole of said lock and said bolt extension and its lug extending across said lock and having bearings against the four inner walls thereof, substantially as described. 55

7. In a safety lock for a switch stand, the combination with the body of a stand provided with a lug having a notch; a pivoted lever having a recess provided with a lock adapted to be operated by a key and a plate 60 on said lock making the same substantially water tight in said recess, said lock having a sliding bolt adapted to engage said notch; a spring normally forcing said bolt downward; and said bolt provided with an integral sliding extension having a lug extending from one face of the lock to the other, and adapted to move across the key hole of 65 said lock when the bolt is in its extreme downward position, and said bolt and extension extending across said lock and having bearings against the opposite walls thereof, substantially as described. 70

In testimony whereof I affix my signature, in presence of two witnesses.

RICHARD FELDER JACOB.
